ELECTRIC DISCHARGE TUBE

Felix Herriger, Berlin, Germany, assignor to C.
Lorenz Aktiengesellschaft, Berlin-Tempelhof,
Germany, a company

Application September 24, 1940, Serial No. 358,068
In Germany October 26, 1939

1 Claim. (Cl. 250—27.5)

This invention is concerned with flat cathodes of the kind employed in electron tubes. More particularly the invention relates to cathodes which comprise a flat carrier body and an emissive layer fitted to it on only one side thereof, namely, the side on which the other electrodes, as anode and grid, are located.

In the copending application of E. Löpp et al., Serial No. 289,644, filed August 11, 1939, a cathode is described which on the other or opposite side of the flat carrier body, that is, the side having no emissive layer, is covered with a protective layer in order to prevent the carrier body, made of nickel, for instance, from volatilizing or evaporating on this side during the operation of the tube. According to this copending application such protective layer may consist of an alkaline earth oxide or may be a ceramic disc.

According to the invention described hereafter it is proposed that a radiation inhibiting layer be arranged to constitute the protective layer, as will be understood from the following description. The accompanying drawing shows a dia-

grammatic sectional view of an electron tube whose cathode is an example of devices as provided by the invention.

In a vacuum vessel 1 an anode 2, a grid 3 and 5 a cathode are contained. The cathode comprises a flat metallic carrier body 4, an emissive layer 5 arranged to face the grid, and a radiation inhibiting layer 8 on the side remote from the grid. Layer 8 comprises a highly polished metal which has an optical radiating capacity less than that of the carrier body 4. As a result this body is prevented from volatilizing, whereby the heating power to be supplied to it is considerably less than in prior devices.

15 15. What is claimed is:

A discharge tube having a cathode which comprises a flat metallic carrier body, an emissive layer fitted to this body on one side thereof, and a radiation inhibiting layer fitted to the carrier body on the other side, said radiation-inhibiting layer comprising a highly polished metal 20 having an optical radiating capacity less than that of the carrier body.

FELIX HERRIGER.
